STAPLE DRIVING MACHINE

Filed Aug. 3, 1927

UNITED STATES PATENT OFFICE

FRIDOLIN POLZER, OF NORWALK, CONNECTICUT, ASSIGNOR TO THE E. H. HOTCHKISS COMPANY, OF NORWALK, CONNECTICUT, A CORPORATION OF CONNECTICUT

STAPLE-DRIVING MACHINE

Application filed August 3, 1927. Serial No. 210,301.

This invention relates to staple driving machines, and may be used either in the so-called tacker type of machine in which for example the staples are driven through a tag 5 to attach it to a shipping box, or a so-called stapling machine in which the staples are driven through two or more sheets of paper and clinched on the under side thereof to secure the sheets together by means of an 10 anvil usually mounted on a base pivoted to the housing or upper section of the machine. As shown in the drawing it is illustrated as applied to a tacking machine although it will be understood the same mechanism may be 15 used for a so-called stapling machine in which an anvil is used to cooperate with the plunger to clinch the staples.

This invention relates to the type of machine in which the staple driving plunger is 20 operated by means of a spring to drive the staple and the operator on each operation compresses this spring and then releases the plunger for the driving operation.

It is an object of the invention to provide 25 a construction of this type which is much more simple than that now generally applied, and therefore, may not only be manufactured and assembled at less cost but is much more reliable in operation as it is less liable to get 30 out of order.

It is also an object of the invention to provide an improved means for actuating the plunger to compress the spring, and release the plunger for the driving operation, and 35 it is a still further object of the invention to provide improved cushioning means for the plunger.

Another object is to provide an improved feeding means for the staples.

With the foregoing and other objects in view, I have devised the construction illustrated in the accompanying drawing forming a part of this specification. In this drawing,

Fig. 1 is a vertical longitudinal section through the device showing the elements in the normal position of rest.

Fig. 2 is a similar view showing the plunger partially retracted and the elements in 50 the position they occupy a short time prior

to the release of the plunger for the staple driving operation.

Fig. 3 is a detail section substantially on line 3—3 of Fig. 2.

Fig. 4 is a detail elevation looking from 55 the front with the plate section in front of the staple guide removed, and

Fig. 5 is a detail plan view of the plunger operating ratchet.

The device comprises a housing 10 of any 60 desired shape having a handle portion 11 for proper handling of the device. Mounted in a slot extending longitudinally in the lower portion of the housing is a supporting bar 12 for the staples 13 of substantially 65 U-shape so that they straddle the top of this bar with the prongs in the vertical position and pointed downwardly. There is sufficient clearance along the sides of the bar at the upper portion thereof between the sides 70 of the bar and the walls of the housing to give the proper clearance for the staples. The bar and walls of the housing thus form a suitable guide for the staples as they are fed 75 to the driving position. The staples may be separate or disconnected staples or they may be in strips of preformed staples held together by any suitable means so that they are easily separated by action of the plunger. They are fed forward in the present construction by means of a follower 14 of inverted U-shape in cross section to straddle the bar 12 and engage at its forward end the staples on this bar, and it is guided by the bar and the walls of the housing. The side 80 walls of the housing may overhang, as shown at 15, to engage the top of this follower or a block 16 mounted on the follower to retain it in proper position on the bar. A coiled spring 17 of flat metal is mounted on a transverse pin 18 to which one end is connected and its free end is connected to a handle stud 19 having a socket therein to receive a pin 20 carried by the follower. It is preferred that this pin be inclined backwardly somewhat as indicated, so that the pull of the spring will tend to retain the handle on the pin, but it will be apparent 95 this handle may be easily lifted upwardly from the pin to release the follower and per-

mit it to be removed by sliding it off the rear end of the bar 12 so that a new supply of staples may be inserted from this end into the guide.

At the front of the housing is a guideway 23 for a plunger 24 so that the plunger may reciprocate up and down across the front end of the bar 12. The lower portion 25 of this plunger is reduced somewhat in thickness so as to provide a shoulder 26 and to make this portion 25 of substantially the thickness of the width of the staple, and therefore, the portion of the guideway at the front of the bar 12 will guide the staple during the driving operation and will retain it in the upright or proper position for driving so that it is driven straight. Above this guideway 23 the housing has an enlarged guideway 27 for a block 28 which is in reality a part of the plunger, and either may be made in one piece with it or made as a separate element to which the lower portion of the plunger is connected as by a pin 29. This construction forms at the bottom of this guideway a shoulder 30 on which rests a helical spring 31 embracing the plunger which forms a cushion or buffer to arrest movements of the plunger should the device be operated when not held against work. It will be apparent that without this spring there will be a severe hammer on the housing or mechanism if the machine were so operated without the spring 31. Above the plunger block 28 is another helical spring 32 engaging the top of this plunger and preferably seated within a recess therein. At its upper end it seats within a recessed disc 33 which is mounted on the end of an adjusting screw 34. To retain this disc in proper relation to the screw the screw has a reduced end 35 seated in an opening in the disc. The screw 34 is threaded in the top plate 36 which is detachably mounted on the housing and a removable front plate 37 by means of the screws 38. By adjusting the screw 34, the tension of the spring 32 may be adjusted and then the screw may be locked in adjusted position by the lock nut 39. It is preferred that the removable front plate 37 be made in two sections, the lower section 40 at the lower part of the machine in front of the guide bar 12 being removable independently of the upper section to give access to the forward part of the guideway for the staples and the guideway for the plunger should there be any closing.

The plunger is operated by being lifted vertically and then released so that it is forced downwardly by the spring 32 to drive the staples. At the rear of the plunger block 28 is a rotatable ratchet wheel 41 mounted to turn on a transverse pin 42. This wheel has any desired number of teeth 43 in position so that as the wheel is rotated these teeth will successively engage the lower shoulder 44 of

the plunger block 28, and therefore, lift the plunger against the action of the spring 32 and compress this spring. This ratchet wheel is rotated with a step by step movement by means of a pawl 45 pivoted at 46 to a hand lever 47. This lever is pivoted in the housing at 48, and the wheel 41 has a central groove 49 at the bottom of which are notches 50 of the same number as the number of teeth on the wheel and arranged to receive the lower end of the pawl 45. This pawl is held against the bottom of the groove by means of a spring 51. The lever 47 is normally held in the upper position, as shown in Fig. 1, by means of a spring 52 seated at its lower end in a recess 53 in the housing and at its upper end embracing a pin 54 mounted on the lever 47. The toothed wheel 41 is so proportioned with respect to the movement of the lever 47 that if the free end of this lever is depressed or forced downwardly as indicated, in Fig. 2, one of the teeth 43 of the wheel will engage the under shoulder 44 of the plunger and will raise the plunger as the wheel is turned to the right or clockwise, as viewed in the figure. The lever 47 has sufficient movement so as to turn the wheel sufficiently to allow the tooth which has raised the plunger to slide off the shoulder 44 and thus release the plunger. This permits the spring 32 which has been compressed by the upward movement of the plunger to force the plunger downwardly to the position of Fig. 1 and drive the staple which was in the guideway beneath the lower end of the reduced portion 25 of the plunger. It will be noted from Fig. 1 that this portion of the plunger is of sufficient length to extend to the lower end of the guideway or that is to the bottom edge of the bar 12 to insure that the staple is properly driven. The housing may also have a stop wall 55 to be engaged by the shoulder 26 on the plunger to limit its downward movement. As soon as the lever 47 is released it is again moved upwardly to the position of Fig. 1 bringing the free end of the pawl 45 into the next notch 50 in the wheel, and the machine is now ready to repeat the operation and drive another staple. It will, of course, be obvious that as the staples are driven the remaining staples are fed forwardly on the bar 12 by spring 17 acting through the follower 14 bringing these staples successively into the proper driving position under the reduced portion 25 of the plunger.

It will be apparent that the device is extremely simple in construction, and therefore, may be manufactured and assembled at comparatively low cost, and will be reliable in operation. The toothed ratchet wheel 41 is of rugged construction and has an extended bearing surface for each set of teeth on the plunger block 28, it being apparent from Fig. 5 that there are really two sets of these teeth.

This element may be made of properly tempered steel so that it will wear for a long time, and as the location of the wheel automatically moves the teeth from engagement with the shoulder 44 on the plunger the operation of releasing the plunger is positive, so that it will be sure to operate and will only operate at a given time or given position of the operating lever. The helical type of springs shown are the most reliable in operation as they have a longer life and are less liable to breakage. It is also easier to make springs of this type of a uniform quality.

Having thus set forth the nature of my invention, what I claim is:

1. In a staple driving machine, a housing, a staple guide in the housing, a reciprocable plunger movable transversely of said guide for driving the staples, a spring for shifting the plunger to drive a staple, a rotatable wheel having teeth arranged to engage a shoulder connected to the plunger to shift said plunger against the action of the spring, and means for rotating said wheel with a step by step movement to alternately retract the plunger and then release it to permit operation thereof by said spring.

2. In a staple driving machine, a reciprocable plunger for driving the individual staples and provided with a shoulder, means for feeding the staples to the driving position under the plunger, a spring for forcing the plunger forwardly to drive a staple, a rotatable ratchet wheel having teeth to successively engage said shoulder and retract the plunger against said spring, and means for rotating said wheel with a step by step movement.

3. In a staple driving machine, a reciprocable plunger for driving the individual staples and provided with a shoulder, means for feeding the staples to the driving position under the plunger, a spring for forcing the plunger forwardly to drive a staple, a rotatable ratchet wheel having teeth to successively engage said shoulder and retract the plunger against said spring, a pivoted lever, a pawl carried by the lever, and said wheel having spaced shoulders cooperating with the pawl to rotate the wheel with a step by step movement as the lever is swung on its pivot.

4. In a staple driving machine, a reciprocable plunger for driving the individual staples and provided with a shoulder, means for feeding the staples to the driving position under the plunger, a spring for forcing the plunger forwardly to drive a staple, a spring embracing the plunger and forming a cushioning means for the plunger at the end of the driving operation, a rotatable ratchet wheel having teeth to successively engage said shoulder and retract the plunger against said spring, a pivoted operating lever, and a one

way driving connection from said lever to said wheel.

5. In a staple driving machine, a reciprocable plunger for driving the individual staples and provided with a shoulder, means for feeding the staples to the driving position under the plunger, a spring for forcing the plunger forwardly to drive a staple, a rotatable ratchet wheel having teeth to successively engage said shoulder and retract the plunger against said spring, a pivoted hand lever, a pawl pivoted to said lever, said wheel having shoulders to engage the end of the pawl whereby said wheel may be rotated with a step by step movement, a spring holding the pawl against the wheel, and a spring tending to hold the lever in the retracted position in preparation for the next staple driving operation.

In testimony whereof I affix my signature.
